Design No. 501.

H. S. Vender

Cook stove Design

Patented September 14, 1852

Des. 501

N. S. Vedder of Troy, N.Y.
Letters Patent No. 501 Dated Sept. 14, 1852.

The schedule referred to in these Letters Patent and making part of the same
To all whom it may concern:

Be it known that I, N. S. Vedder of Troy in the

County of Rensselaer, and State of New York, have invented or produced a new and original design of Cook Stove which I call the "Beauty of the West," and I do hereby declare that the following is a full, clear and exact description of the same reference being had to the annexed perspective drawing making a part of this specification.

The ornamental design of my stove consists in the arrangement of the rosettes (a a) on the panels of the fire and oven doors of the jamb A, and front doors of the plate B, as represented, and in the combination of the mouldings (b b) forming the frames of the oven, fire and front doors jamb and front plate.

Having thus described my design of cook stove, what I claim as new and desire to secure by Letters Patent, is the ^{ornamental} design and configuration of cook stove the same as herein described, and represented in the annexed drawing.
